ATTORNEY.

UNITED STATES PATENT OFFICE

JOHN H. GRININGER, OF ST. PAUL, MINNESOTA

WINDOW WEDGE

Application filed March 26, 1928. Serial No. 264,756.

This invention relates to a new and useful article of manufacture which might most aptly be termed an expanding wedge latch particularly useful for holding and latching a window in any position and positively eliminating rattling of such window in its frame. The object of the invention is to provide a simple, highly efficient and inexpensive device for the purpose set forth.

10 The following specification reveals the detail construction and operation of the device and as illustrated in the accompanying drawing, in which,—

Fig. 1 is a vertical rear view of the device 15 in readiness for use.

Fig. 2 is a central longitudinal sectional elevation as on line 2—2 in Fig. 1.

Fig. 3 is a top view of my device in operative position at an upper corner of a window.

20 Fig. 4 is a front view of Fig. 3 taken about as on line 4—4 in said Fig. 3.

Fig. 5 is an elevation of a preferred type of actuating lever used in the wedge device.

For the purpose of simplifying description of the device it will hereinafter be designated simply as window-wedge or expanding wedge and referring to the drawing by reference numerals, I have shown my device as applied in latching an upper corner of a 30 window 10, guided between a parting strip 11, a moulding 12 and the upright side window frame member 13.

The main object of this invention is to prevent rattling of a window, which fits loosely 35 in the frame between the opposite members 13 and as a consequence of which there is an opening 14 between the vertical edge of the window and the adjacent member 13 (see Figs. 3 and 4).

40 The window wedge comprises three metal members which might most conveniently be termed the main or outer wedge, the secondary or inner wedge and the actuating lever 15, the device being shown in Figs. 1 and 45 2 as closed in readiness for use. The main wedge member comprises a single piece of flat spring-bar metal 16 doubled as at 16D to form the thin edge of the wedge and above said closed part both arms of the member lie 50 against each other for a predetermined dis-

tance, thence are spread apart gradually, one arm terminating and formed in a transverse bearing 16B for a transverse shaft 15A formed integrally with the lower end of lever 15, while the other arm extends above said bearing 16B and terminates preferably in an inverted U-shaped form 16C within the curvature of which is frictionally retained the transverse bearing part 17B of the secondary wedge. Said latter bearing, 17B comprises 55 the upper end part of the secondary wedge which is of bar material similar to the main wedge, the bearing part adapted to engage an upper transverse shaft 15B of lever 15 parallel to shaft 15A both said shafts and the bearing members 16B and 17B being normally in a common vertical plane when the device is closed and the upper part of the lever extending of course vertically therefrom above the wedges. In the drawing the 60 free end of lever 15 is illustrated as a loop 65 15L forming a convenient finger-hold.

Below the bearing 17B of the secondary wedge it is closed under the shaft 15B and its two arms extend downwardly within the 70 spread upper arms of the main wedge, one arm preferably terminating as at 17A further down within the main wedge, the lower end of the short arm being designated 17C (see 75 Figs. 1, 2 and 4).

In the use of the wedge device it is inserted, 80 while in closed condition as in Fig. 2, with its wedge end 16D downwardly into space 14 as far as possible without forcing it down, it being understood that the lever 15 is extending upwardly in alinement with the wedge proper and being of course close to the face of the window frame member. Then the lever is swung down and inwardly over the adjacent window top as indicated by arrows 18 swinging the shafts 15A—15B to a horizontal plane, or even with shaft 15B below said plane, this action thus forcibly spreading the upper ends of the main wedge arms apart, causing the window 10, to be 85 firmly engaged and pressing it horizontally to bear tightly against the opposite side window-guide means (not shown). The rear arm of wedge 16 is of course pressed against the 90 frame member 13 and bearing 17B is sta- 95 100

tionary. However, during this swinging of lever 15 it is obvious that bearing 17B is forced inwardly and down from its normal position vertically above bearing 16B and this of course moves the secondary wedge 17 downwardly between the arms of the main wedge 16 thus providing further forced wedging or spreading of the member 16 as the ends 17A and 17C move downwardly (see Fig. 4). Ordinarily one of these devices is sufficient to hold a slidable window tight. It is obvious that the device being used on the upper corner of a window the latter may be raised slightly from its lowest position to admit fresh air into a room. The amount of opening required at the bottom may be very small or insufficient for any burglar or prowler to force the window up any further except by deliberate destruction of it.

20. I claim:

An expanding wedge comprising a main wedge member of flat metal folded at approximately its center to form the point of the wedge, one end of said main wedge comprising a transverse bearing, a secondary wedge member within the upper part of the main wedge and comprising a similar flat bar formed with a transverse bearing at its middle and two arms normally flat against each other below said bearing, the other end of said main wedge formed in inverted U-shape and opening toward its adjacent bearing but in spaced relation upwardly thereof and arranged to frictionally engage the bearing of the secondary wedge, an elongated forked handle with two spaced transverse shafts fixed in the lower part of its fork, said bearing of the main wedge arranged to engage the outermost of said shafts of the handle and said bearing of the secondary wedge arranged to engage the other shaft normally above the first bearing.

In testimony whereof I affix my signature.

JOHN H. GRININGER.
